(57) **CLAIM**

The ornamental design for an integrated baffle design for a loudspeaker, as shown and described.

DESCRIPTION

FIG. 1 is a front perspective view of an integrated baffle design for a loudspeaker showing my new design; and, FIG. 2 is a front elevational view thereof.

The broken lines showing the enclosure in FIGS. 1 and 2 are merely illustrative of the environment of use and are not part of the claimed design.

1 Claim, 2 Drawing Sheets

FIG. 1

FIG. 2
